UNITED STATES PATENT OFFICE

ROBERT BEARDSLEY, OF CHICAGO, ILLINOIS

BEAD FORMER

Application filed April 4, 1927. Serial No. 180,927.

This invention relates to new and useful improvements in bead forming devices, particularly adapted for use in beading lamp shades, and is a division of my copending 5 applications, namely—a method of and apparatus for forming articles, filed November 30, 1923, Serial No. 677,719, and method of and apparatus for forming articles from paper and the like, filed July 13, 1925, Serial 10 No. 43,291.

One of the objects of my invention is the provision of a new and improved embossing or beading device, which will be simple, inexpensive, durable, reliable, efficient and satisfactory for use wherever found applicable.

Many other objects and advantages of the construction herein shown and described will be obvious to those skilled in the art from the disclosure herein given.

20 To this end my invention consists in the novel construction, arrangement and combination of parts herein shown and described, and more particularly pointed out in the claims.

25 In the drawings, wherein like reference characters indicate like or corresponding parts:

Fig. 1 is a plan view of one form of my improved embossing or beading device;

30 Fig. 2 is a section taken on line 2—2 of Fig. 1;

Fig. 3 is a top plan view of another form of beading device;

Fig. 4 is a sectional view taken on the line 35 4—4 of Fig. 3;

Fig. 5 is a sectional view of a lamp shade prior to beading; and

Fig. 6 is a detail sectional view of a lamp shade showing the bead completed.

40 My improved apparatus for forming the bead upon the formed blank A comprises a base plate 1 upon which is mounted a holder 2 having a frustro-conical aperture 3 conforming to the shape of the formed blank A in Fig. 5. Secured to the base plate 1 and concentrically disposed in the aperture 3 is a plate 4 adapted to support the top blank B when the same is placed in the aperture 3 in the manner illustrated in Fig. 2. As

45 shown, the formed article will project above

the holder 2 so that its upper circular edge will be disposed in alignment with arcuate grooves 5 formed in a pair of arcuate levers 6 which are pivotally secured to the base plate 1 by a bolt 7, the free end of the levers 6 being provided with handles 8 whereby the levers may be swung into and out of the positions wherein they are shown in Fig. 1.

Projecting upwardly from the base 1 and centrally disposed with respect to the aperture 3 is a pin 9 having a portion 10 of reduced diameter.

55 Rotatably journaled upon the portion 10 is a bracket member 11 which carries a pin 12 pivotally securing a lever 13 to the bracket member, the longitudinal axis of the pin 12 being disposed at right angles to the longitudinal axis of the pin 9. Rotatably journaled upon the lever 13 is a wheel 14 which may be rolled around the inner surface of the formed blank A to expand the marginal portion C thereof into the annular grooves 5, which will form a bead 15 as shown in Fig. 2. As shown in Figs. 1 and 2, a latch member 16 pivotally secured

60 to one of the arcuate levers 6 may be employed to lock the levers in the positions wherein they are shown in Fig. 1. After the bead 15 has been formed, the levers 6 are swung out of the positions wherein they are shown in Fig. 1 and the bracket member 11 65 together with the lever 13 and the wheel 14 are removed from the holder 2. From this it will be apparent that the formed blank A can be quickly placed in position for beading the marginal portion C or removed from

70 the device.

To prevent distortion of the formed article when the bead 15 is being produced and to hold the formed articles against displacement relative to the holder 2, I preferably provide a weight 17 adapted to be inserted into the formed blank A to hold it in engagement with the frustro-conical surface of the aperture 3. The weight 17 is preferably provided with a plurality of eyes 18, or the equivalent, whereby the operator may lift the weight from the holder 2.

75 It will be apparent from the foregoing that in the use of my improved device, the formed blank A is first placed in the holder 100

3 and the weight 17 then positioned to hold the blank in place. The arcuate levers 6 are then moved to a closed position to embrace the marginal edge C of the formed blank as shown in Fig. 1, and in order to form the bead 15, the wheel 14 is rotated in the grooves 5 pressing a portion of the blank therein, as shown.

In Figs. 3 and 4, I have shown another form 10 of the invention which comprises a chambered part 19 having its inner wall shaped to smoothly engage the outer periphery of the shade but being slightly shorter than the formed blank shade A so that the shade will 15 project therebeyond a suitable distance. An inner sleeve 20 is removably positioned within the shade after it has been placed in the mold, this sleeve being of substantially the same length as the part 19.

20. A ring member, made in one or more sections, there being two parts shown, as at 21 and 22, is arranged to encircle the projecting portion of the shade, said ring member having an annular groove provided therein and into 25 which the projecting portion of the shade is pressed or rolled. The parts 21 and 22 are pivotally mounted upon an upright part 23 and have projecting handle portions 24, whereby they may be swung into or out of 30 operative position and held in place during the embossing.

A roller 25 having a convex peripheral edge to cooperate with the annular groove in the ring is mounted upon a handle 26, the lower 35 end of said handle having a ball thereat which is mounted in a spherical socket bearing 28, whereby the roller may be given a universal movement. Springs 29 are mounted upon the tightening bolts 30 and positioned between 40 the clamping plate 31 and the socket bearing 28 so that the bearing for the ball 27 may be adjusted when desired. After the shade has been arranged in place between the parts 19 and 20, the hand grip 32 of the handle 26 45 is grasped and rotated so that the roller 25 engages the inner periphery of the projecting portion of the shade and expands or bulges it radially outwardly into the groove formed in the ring 21-22. This is sufficient to shape 50 the shade at this end and form a bead thereat. The shade may then be removed from the mechanism and treated in any suitable manner, dependent upon the purpose for which it is to be used.

55. It will be apparent from the foregoing that I have provided a new and improved device which will prove extremely useful in embossing or beading formed lamp shades. It will also be readily apparent that the 60 formed shades may be quickly and readily placed in the device and after being beaded can be quickly removed. The device may also be used equally as well for embossing or beading articles other than lamp shades.

65. Having thus described my invention, it is

obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A bead former comprising a pair of inner and outer annular members adapted to hold a shade therebetween so that one edge of the shade may extend therebeyond, a ring about said projecting edge of said shade, a roller element, and means for mounting said last-mentioned element so that it may be rolled against said projecting edge of the shade to press it against said ring to form a bead therein.

2. A bead former for lamp shades comprising a pair of inner and outer annular members adapted to hold a shade therebetween so that one edge of said shade may extend therebeyond, a ring member having a groove therein, means for holding said last-mentioned member adjacent said projecting edge of the shade, and a roller element revolvably mounted so that it may be rolled outwardly against said projecting edge of the shade so as to press it into the groove of said ring member.

3. A bead former for lamp shades comprising a pair of inner and outer annular members adapted to clamp a shade therebetween, said inner member being removable, one edge of said shade adapted to extend beyond said members, a ring-like member having a groove therein, means for mounting said last-mentioned member about said projecting edge of the shade, a roller element, a handle carrying said roller element, and means for mounting said handle so that it may be revolved to press the roller outwardly against the inner surface of the projecting edge of the shade to press it into said groove of the ring-like member.

4. In a device of the class described, a holder having a frusto-conical aperture therein for accommodating a sheet of flexible material, a pair of pivoted arcuate members each having a groove therein and so disposed in relation to said holder that said grooves may be arranged with their surfaces constituting a continuation of the frusto-conical surface of said holder, and means for expanding an annular portion of said sheet into said grooves.

5. In a device of the class described, a holder having a frusto-conical aperture therein for accommodating a sheet of flexible material, a pair of pivoted arcuate members each having a groove therein and so disposed in relation to said holder that said grooves may be arranged with their surfaces constituting a continuation of the frusto-conical surface

of said holder, means for manipulating said arcuate members, means for locking said members with their grooved surfaces in continuation of the surface of said frusto-conical member, and means for expanding an 5 annular portion of said sheet into said grooves.

6. In a device of the class described, a holder having a frusto-conical aperture therein for accommodating a sheet of flexible material, a pair of pivoted arcuate members each having a groove therein and so disposed in relation to said holder that said grooves may be arranged with their surfaces constituting 10 a continuation of the frusto-conical surface of said holder, a frusto-conical member adapted to coact with said holder for securing said flexible sheet therein, said frusto-conical member being bodily removable from 15 said holder, and means for expanding an annular portion of said sheet into said grooves.

7. In a device of the class described, a holder having a frusto-conical aperture therein for accommodating a sheet of flexible material, a pair of pivoted arcuate members each having a groove therein and so disposed in relation to said holder that said grooves may be arranged with their surfaces constituting 20 a continuation of the frusto-conical surface of said holder, means for manipulating said arcuate members, means for locking said members with their grooved surfaces in continuation of the surface of said frusto-conical member, a frusto-conical member adapted to coact with said holder for securing said flexible sheet therein, said frusto-conical member being bodily removable from said holder, and means for expanding an annular 25 portion of said sheet into said grooves.

8. In a device of the class described, a holder having a frusto-conical aperture therein for accommodating a sheet of flexible material, a pair of pivoted arcuate members each 30 having a groove therein and so disposed in relation to said holder that said grooves may be arranged with their surfaces constituting a continuation of the frusto-conical surface of said holder, and a manipulable member 35 swivelled within said holder and having means thereon adapted to coact with said grooves for forming an annular bead in said flexible sheet.

9. In a device of the class described, a holder having a frusto-conical aperture therein for accommodating a sheet of flexible material, a pair of pivoted arcuate members each having a groove therein and so disposed in relation to said holder that said grooves 40 may be arranged with their surfaces constituting a continuation of the frusto-conical surface of said holder, means for manipulating said arcuate members, means for locking said members with their grooved surfaces 45 in continuation of the surface of said frusto-

conical member, and a manipulable member swivelled within said holder and having means thereon adapted to coact with said grooves for forming an annular bead in said flexible sheet.

10. In a device of the class described, a holder having a frusto-conical aperture therein for accommodating a sheet of flexible material, a pair of pivoted arcuate members each having a groove therein and so disposed in relation to said holder that said grooves may be arranged with their surfaces constituting a continuation of the frusto-conical surface of said holder, a frusto-conical member adapted to coact with said holder for securing said flexible sheet therein, said frusto-conical member being bodily removable from said holder, and a manipulable member swivelled within said holder and having means thereon adapted to coact with said grooves for forming an annular bead in said flexible sheet.

11. In a device of the class described, a holder having a frusto-conical aperture therein for accommodating a sheet of flexible material, a pair of pivoted arcuate members each having a groove therein and so disposed in relation to said holder that said grooves may be arranged with their surfaces constituting a continuation of the frusto-conical surface of said holder, means for manipulating said arcuate members, means for locking said members with their grooved surfaces in continuation of the surface of said frusto-conical member, a frusto-conical member adapted to coact with said holder for securing said flexible sheet therein, said frusto-conical member being bodily removable from said holder, and a manipulable member swivelled within said holder and having means thereon adapted to coact with said grooves for forming an annular bead in said flexible sheet.

In testimony whereof, I have hereunto signed my name.
